Patented Nov. 11, 1975

237,629

COMBINED ANIMAL OILER AND SCRATCHER

George W. Keene, P.O. Box 395, Rochelle, Ill. 61068

Filed Apr. 4, 1974, Ser. No. 457,924

Term of patent 14 years

Int. Cl. D30—99

U.S. Cl. D30—99

FIG. 1 is a top plan view of a combined animal oiler and scratcher showing my new design;

FIG. 2 is a left side elevational view;

FIG. 3 is a front elevational view; and

FIG. 4 is a right side elevational view.

I claim:

The ornamental design for a combined animal oiler and scratcher, substantially as shown and described.
